UNITED STATES PATENT OFFICE.

FREDERICK B. POWER, OF WASHINGTON, DISTRICT OF COLUMBIA, AND VICTOR K. CHESNUT, OF HYATTSVILLE, MARYLAND.

SYNTHETIC APPLE-OIL.

1,366,541.

Specification of Letters Patent. Patented Jan. 25, 1921.

No Drawing.

Application filed July 19, 1920. Serial No. 397,498.

(FILED UNDER THE ACT OF MARCH 3, 1883, 22 STAT. L., 625.)

To all whom it may concern:

Be it known that we, FREDERICK B. POWER and VICTOR K. CHESNUT, citizens of the United States of America, and employees of the Department of Agriculture, residing in Washington, District of Columbia, and Hyattsville, Maryland, respectively, (whose post-office address is Department of Agriculture, Washington, D. C.) have invented 10 a new and useful Synthetic Apple-Oil.

This application is made under the act of March 3, 1883, chapter 143 (22 Stat., 625), and the invention herein described and claimed may be used by the Government of 15 the United States or any of its officers or employees in the prosecution of work for the Government, and by any person in the United States, either in public or private work, without payment to us of any royalty 20 thereon.

Our invention relates to a synthetic apple oil and any combinations or mixtures that may be prepared therefrom. The production of our synthetic apple oil is based upon 25 the results of extensive chemical investigations of the odorous constituents of fresh ripe apples, the nature of which has not heretofore been known.

Our synthetic apple oil is composed of the 30 amyl esters of formic, acetic, caproic, and caprylic acids, together with acetaldehyde, and these substances when mixed in suitable proportions, represent in a highly concentrated form the fragrant odor of fresh apples. This preparation may be used to impart the true odor of apples to various articles of food and beverages, or as a general flavoring agent. The proportions by volume of the various constituents of the oil 35 40 which have been found most suitable for the purpose intended, and which should be em-

ployed in the purest possible state, are as follows:

Iso-amyl ester of formic acid	10 parts	45
Iso-amyl ester of acetic acid	10 parts	
Iso-amyl ester of normal caproic acid	5 parts	
Iso-amyl ester of normal caprylic acid	1 part	
Acetaldehyde	2 parts	50

It has been found that a satisfactory synthetic apple oil may be obtained by omitting from the above combination of ingredients the iso-amyl ester of normal caprylic acid. 55

The above mentioned combinations which are not restricted to the exact proportions indicated may be employed for flavoring purposes either in its concentrated state or in the form of a solution in pure ethyl alcohol, in a mixture of alcohol and glycerin, and with alcoholic solutions of certain organic acids, such as citric and tartaric acids, or it may be brought into the form of an emulsion with certain fatty oils, especially such as 60 have the least tendency to become rancid on keeping. 65

We claim:

1. A synthetic apple oil consisting of the amyl esters of formic, acetic, caproic, and 70 caprylic acids, together with acetaldehyde.
2. A synthetic apple oil consisting of a mixture of the amyl esters of formic, acetic, caproic acids, together with acetaldehyde. 75

In testimony whereof, we affix our signatures in the presence of two subscribing witnesses.

FREDERICK B. POWER.
VICTOR K. CHESNUT.

Witnesses:

JOSEPH COHEN,
O. C. COTT.
